UNITED STATES PATENT OFFICE.

FRED S. CARR, OF NEWTON, MASSACHUSETTS, ASSIGNOR TO CARE FASTENER COMPANY, OF CAMBRIDGE, MASSACHUSETTS, A CORPORATION OF MAINE.

FASTENER.

Application filed June 14, 1924. Serial No. 719,933.

This invention aims to provide an improved separable fastener.

In the drawings, which illustrate a preferred form and a modified form of my invention:—

Figure 1 is a front elevation of the preferred embodiment of my device;

Fig. 2 is a section on the line 2—2 of Fig. 1, being partly in elevation;

Fig. 3 is a rear elevation of the stud member of the device;

Fig. 4 is a section similar to Fig. 2, showing the stud entering the socket;

Fig. 5 is a section on the line 5—5 of Fig. 2;

Fig. 6 is a front elevation of the latch member of the preferred embodiment of my device; and

Fig. 7 is a cross-section of the modified form of my device, being partly in elevation.

Referring to the form of fastening device illustrated in Figs. 1 to 6 inclusive, I have shown a grommet or eyelet 1 secured to the body of an automobile or like support. In the wooden part 3 of the body of the car, I have provided a recess 4 beyond the eyelet, thereby to permit passage of the head of a stud through the eyelet. Thus a socket is provided which is substantially flush with the side of the car and which has no mechanism which can get out of order.

The stud member may be secured to the curtain 5 in any suitable manner, but I prefer to provide prongs 6 projecting from a front plate 7 through the curtain 5 and slots 8 in a back plate 9. The prongs are then bent into engagement with the back plate, as best illustrated in Figs. 2 and 3. The stud as illustrated includes a relatively short hollow shank 10 pressed from a base plate 11 and passing through the curtain 5 and back plate 9 for engagement with the eyelet 1. The base plate 11 is secured to the front plate 7, as illustrated in Figs. 2 and 4, to provide a casing at the front side of the curtain for reception of a spring plate 12.

The spring plate 12, as illustrated in Figs. 2 and 6, is pressed from a single sheet of metal and comprises a U-shaped portion 12^a, a resilient finger 13 extending from the U-shaped portion 12^a and a latch 14 extending substantially at a right angle to the spring finger. This latch is preferably formed by pressing two like parts from the flat sheet of metal and bending them toward each

other to provide a latch of relatively thick cross-section. The U-shaped portion 12^a is held rigidly in the casing, while the resilient finger 13 is free to flex relative to the casing by providing a depressed portion in the back plate as illustrated. Thus the resilient finger presents the latch in the shank 10. To permit the latch to be exposed at the exterior surfaces of the hollow shank 10, I provide a slot 15 in the shank through which the latch presents a considerable projection in the form of a cam-shaped edge 16 which is normally presented at the lower exterior surface of the hollow shank 10.

Fig. 4 illustrates the proper relation of the stud to the socket when the shank 10 is being entered in the eyelet 1. The diameter of the aperture in the eyelet is enough larger than the diameter of the shank 10 to permit the shank to be entered into the eyelet, while tipped relative thereto, so that the shoulder 17 on the latch 14, normally within the shank 10, may pass by the inner edge of the eyelet before any substantial movement of the latch has taken place.

When the cam-shaped edge 16 of the latch engages the edge of the eyelet, as shown in Fig. 4, and the stud is pressed toward the socket, the latch is forced upwardly and inwardly relative to the shank and against the pressure of the spring finger 13. Thus as the shank passes into the recess 4 in the body 3 of the car, the shoulder of the latch is exposed at the upper exterior surface of the shank 10 through the slot 15 and engages back of the eyelet, as illustrated in Fig. 2, thereby locking the stud with the socket.

When the stud is secured to the socket (Fig. 2) the back plate 9 lies relatively close to the side of the car, thereby positioning the curtain as close to the side of the car as possible, to prevent a lateral strain on the curtain from tipping the stud out of engagement with the socket. The shoulder 17 also prevents separation of the stud from the socket by an outward strain exerted on three sides of the stud, namely at both sides and above the stud as viewed in Figs. 1 and 2.

The shank 10 of the stud is located adjacent that edge of the casing toward the body of the curtain so that the rest of the casing extending toward the free edge of the curtain provides a substantial leverage for separating the stud from the socket when

the lower edge of the curtain is pulled. Locating the shank at the upper edge of the casing permits the curtain to lie close to the body of the car when the stud and socket are engaged while permitting the stud to be tipped out of engagement with the socket without interference between the back plate 9 and the body of the car.

Referring to the modified form of device, 10 illustrated in Fig. 7, I have shown a stud 18 presenting a screw 19 for attaching the stud to a fixed support. This stud presents a shank 20 and a unitary latch 21 and spring finger 22 struck up from a base plate 23 substantially as shown and described in the preferred form of my device.

The grommet or eyelet 25 is secured to the curtain in this instance and the operation of the fastener is substantially the same as described in connection with the first preferred form.

While it is essential that the plane of the curtain be close as possible to that of the body in the first form, such is not the case 25 in the second form because the stud is rigid, and the eyelet cannot become disengaged from the shank by an upward or outward strain on the curtain above the stud.

The purpose of illustration of the modified form of device is to show the adaptation 30 of the unitary spring and latch to other than a flush type fastener.

While I have shown and described a preferred form of one embodiment of my invention, it will be understood that changes 35 involving omission, alteration, substitution and reversal of parts, and even changes in the mode of operation, may be made without departing from the scope of my invention, 40 which is best defined in the following claims.

Claims:

1. A separable fastener comprising, in combination, a socket secured to a rigid support, a stud having a casing secured to that side of a stud-carrying fabric opposite the side adjacent the socket, the shank of the stud extending from a plate forming part of said casing, said shank passing through 50 the fabric for engagement in an aperture presented by said socket and resilient means held in said casing, said means carrying an integral latch passing through the shank of the stud and presenting a portion for engagement with said socket to lock the stud and socket together.

2. A separable fastener comprising, in combination, a socket secured to a rigid support, a stud including a casing secured to the front side of a curtain, a shank portion 60 presented by the opposite side of the curtain for engagement with the socket, a spring plate in said casing carrying a latch passing through said curtain and said shank 65 for engagement with the socket, said latch

having a shoulder thereon for locking said stud and socket together, the curtain and the rigid socket support adapted when said stud and socket are secured together to lie relatively close together thereby to prevent 70 separation of the fastener by lateral strain exerted upon the curtain, said shank being located adjacent to the upper edge of the casing to prevent interference between the stud member and the socket support when 75 said fastener is being separated by a pull at the lower edge of the curtain.

3. A separable fastener comprising, in combination, an eyelet for use as a socket, a stud having a shank portion for engagement with said eyelet, and a spring plate carrying only a single hooked latch integral with said plate, said latch presenting opposed edges through a slot in said shank for engagement with said eyelet when said shank is engaged therewith, thereby preventing separation of said fastener by a pull at three sides thereof, and said spring plate providing spring means normally acting upon the latch so as to withdraw one edge 90 thereof within the shank of the stud when the stud and socket are disengaged.

4. A stud for a separable fastener comprising, in combination, a casing, a shank extending from said casing, a resilient plate held in said casing and a latch integral with said resilient plate, said latch presenting an abrupt shoulder normally withdrawn within said shank by said resilient plate and a cam portion normally exposed at one side of said shank for engagement with a socket to force 100 said abrupt shoulder outwardly from said shank.

5. A flush type fastener comprising, in combination, an eyelet secured to a rigid support thereby to provide a socket, a stud including a casing secured to one side of a flexible curtain, a shank extending from said casing through said curtain for engagement with said eyelet, a plate held in said casing and presenting a spring finger operable in 110 said casing, said spring finger carrying a latch which passes through a slot in said shank, and a shoulder on said latch normally held within said shank, said spring finger 115 operable upwardly and inwardly by engagement of said latch with said eyelet to present said shoulder back of said eyelet, thereby locking the stud with the socket against separation by a pull at three sides thereof.

6. A flush type fastener comprising, in combination, an eyelet secured to a rigid support to provide a socket, a cooperating stud unit having a shank part for engagement with said eyelet, a latch assembled with 125 the stud unit, said latch being shiftable relative to said shank to present a locking shoulder through a slit in the shank for engagement back of said eyelet and a casing also forming part of the stud unit, said casing 130

being secured to one side of a flexible curtain and extending a substantially greater distance at one side of said shank than at the opposite side, said extended portion providing a favorable leverage for tipping said stud out of engagement with the eyelet when the curtain is pulled adjacent to said extending side of the casing.

7. Locking means for a separable fastener comprising a base plate, a resilient portion integral therewith and movable relative thereto and a socket-engaging latch integral with said resilient portion, said latch presenting an abrupt shoulder at one edge for engagement with a socket and at the opposite edge cam means for engagement with a socket to move said shoulder into locking engagement with the socket.

8. A stud and eyelet fastener comprising, in combination, an eyelet adapted for use as a socket, a cooperating stud having a casing, a hollow shank portion projecting from said casing, a spring plate held in said casing carrying a latch member integral with said spring plate, opposite edge portions of said latch member being presented at opposite exterior lateral surfaces of said shank when said eyelet and shank are engaged, an abrupt shoulder at one exterior surface for locking said eyelet to said shank and a cam

portion at the opposite exterior surface engaging said eyelet under tension of said spring plate, said shank and eyelet separable only by a pull adjacent said cam portion.

9. A separable fastener comprising, in combination, a stud member and a socket member, one of said members presenting a shoulder and the other of said members having a casing containing a spring plate member, said spring plate member having a yieldable portion and a latch, said latch having a shoulder for engagement back of the shoulder provided by said first-mentioned fastener member and means for moving said second-mentioned shoulder out of engagement with the first-mentioned shoulder prior to disengagement of the fastener members.

10. A separable fastener comprising, in combination, a socket secured to a rigid support, a stud including a casing secured to the front side of a curtain, and a spring plate in said casing carrying a latch passing through said curtain for engagement with the socket, said latch having a shoulder thereon for locking said stud and socket together.

In testimony whereof, I have signed my name to this specification.

FRED S. CARR.
